Henry J. Lueke

UNITED STATES PATENT OFFICE.

FRANK J. EISENHUT, OF WOODHAVEN, NEW YORK.

TELEPHONE-SUPPORT.

1,274,150.

Specification of Letters Patent. Patented July 30, 1918.

Application filed January 15, 1917. Serial No. 142,380.

To all whom it may concern:

Be it known that I, FRANK J. EISENHUT, a citizen of the United States of America, residing at Woodhaven, county of Queens, 5 State of New York, have invented certain new and useful Improvements in Telephone-Supports, of which the following is a specification.

This invention relates to supports for articles such as telephones of the desk type and similar articles, and is particularly directed to a support comprising a member for carrying the greater part or a whole of the weight of the article, together with 10 means provided with an opening having relatively fixed sides for limiting the extent of movement of the article and means extending within the contour of said opening for yieldably holding said article on said member. Preferably, the yieldable holding means 20 comprises two jaw-like elements movably mounted on a suitable support and movably and resiliently related to one another.

The invention attains the advantages of 25 securely placing the telephone or other article on a support which may be mounted on a wall or on the side of a desk or other article of furniture, thereby leaving the top of the desk free for use for other purposes. 30 The invention also attains the advantage of permitting the telephone or other article to be readily and quickly removed from such support and placed in convenient position relative to the user while at the same time 35 affording protection to the telephone or other article from falling from the support when struck accidentally. A further feature of the invention is that the support does not involve any instrumentality which 40 is attached to or affixed to the telephone proper.

Other features and objects of the invention will be more fully understood from the following detail description and the accompanying drawings, in which—

Figure 1 is a side elevation of a preferred embodiment of the invention, showing a telephone of a desk type as an article supported by means of the invention;

50 Fig. 2 is a front elevation of the same; and

Fig. 3 is a top plan view of the same, with certain portions thereof partly broken away for sake of clearness.

55 Referring to the drawings, the main sup-

porting member is shown as a shelf 1 having the back 2 adapted to be attached to a wall, or onto an article of furniture or the like by means of screws 3. In suitable relation to such member 1 is provided the means 60 for restricting within fixed limits, the movement of the telephone 4, or other article, said restricting means being shown as a projecting member 5 provided with the opening 6 having the fixed sides 7. The particular 65 shape of said opening 6 and the extent of clearance relative to the stem portion 8 of the article will be determined by the nature and manner of use of such article.

The resiliently holding means is illustrated as comprising the coacting duplicate jaw-like elements 9, 9, arranged in juxtaposed relation to one another and having their jaws 10 respectively extending toward the forward portion of said opening 6. Said 75 jaws 10 are shaped to permit ready passage of the article into and out of the opening 6.

Each said element 9 is movably mounted on a suitable support, as by means of a pin 11 extending at one end into the opening 12 disposed within the fixed portion 13 and at the other end into an opening 14 disposed within the rearward portion 15 of such element 9. Said elements 9 are movably mounted relative to one another by means 80 of the pin 16 extending at its opposite ends into openings respectively disposed within intermediate portions of the respective elements 9. The resilient means is shown as comprising two oppositely disposed springs 85 17 positioned between each jaw-like element 9 and a fixed part such as said fixed part 13. Such combination of resilient means and said movable mounting arrangement affords instant relative separation of the forward jaws of the elements 9 to permit entry 90 of the telephone or other article within the opening 6, while attaining a secure hold onto the article after having been placed on the support. In the event that the article is 95 subjected to a relatively light force, the yielding jaws firmly protect the article from falling off of the support. Should a relatively strong force be applied, the fixed sides of the opening 6 will preclude movement 100 beyond the limits defined by said fixed sides.

It will be noted that the relatively delicate holding elements are protected by the projecting member 5, under all conditions of accidents.

For convenience, said projecting member 5, is arranged in duplicate on the opposite faces of said fixed part 13, and said jaw-like elements 9 disposed between said duplicate members 5.

It will also be noted that the projecting member is arranged to preserve the operative relation of the parts of the article to be supported and to this end, in the case of 10 a telephone, the projecting member is sufficiently close to the supporting member to permit the receiver 18 to be freely hung from the telephone hook 19.

As shown, it is convenient for manufacture and assembling, although not essential to the invention, that the resilient means be of the form of duplicate flat springs, and positioned between each jaw-like element and a fixed support loosely within a suitable recess and the ends of the springs lodged within suitable recesses respectively in said jaw-like elements. Also, for reasons of simplicity of manufacture and assembly, although not essential to the invention, the 20 mounting means comprise round pins inserted in suitable openings in the respective jaw-like elements and the fixed support.

Whereas I have described and illustrated my invention by reference to specific embodiment thereof, it will be understood that modifications and changes may be made 30 without departing from the invention.

I claim—

1. A holder for telephones and the like, comprising a base, means in stationary relation to said base for receiving a portion of the article, said means including fixed arms having their free ends spaced one from another to form an open sided receiving aperture, and means for yieldingly engaging a portion of the article, said yielding means including movable arms having their free ends normally extending within the contour of said receiving aperture and means normally holding the free ends of said arms in spaced relation. 35

2. A holder for telephones and the like, comprising a base, means in stationary relation to said base for receiving a portion of the article, said means including fixed 40 arms having their free ends spaced one from another to form an open sided receiving aperture, and means for yieldingly engaging a portion of the article, said yielding means including movable arms having their free ends normally extending within the contour of said receiving aperture and means normally holding the free ends of said arms in spaced relation. 45

In testimony whereof I have signed this specification this 13th day of January, 1917.

FRANK J. EISENHUT.
